George J. Dochtermann
Wilbert McStone.

UNITED STATES PATENT OFFICE.

GEORGE T. DOCHTERMANN, OF PASSAIC, NEW JERSEY.

DISTRIBUTER-HEAD FOR MAGNETOS.

1,289,128.

Specification of Letters Patent. Patented Dec. 31, 1918.

Application filed April 10, 1918. Serial No. 227,876.

To all whom it may concern:

Be it known that I, GEORGE T. DOCHTERMANN, a citizen of the United States, and a resident of Passaic, in the county of Passaic and State of New Jersey, have invented certain new and useful Improvements in Distributer-Heads for Magnetos, of which the following is a specification.

This invention relates to distributor heads for magnetos and other electrical instruments in which the electrical circuit is broken at regular predetermined intervals.

The object of my improvements is to provide a device of the class specified in which the parts are of simple and long wearing construction and in which the contact of the make and break members is of relatively long duration. Other objects will appear later herein.

20 My improved head is illustrated in its preferred embodiment in the drawings accompanying this specification wherein Figure 1 is a sectional elevation of so much of a distributor head as will suffice to show my improvements. Fig. 2 is a bottom plan view of what is shown in Fig. 1 with the distributor disk removed. Fig. 3 is a sectional elevation of the distributor disk looking in the direction of arrow 3 of Fig. 1. Fig. 4 is a 25 sectional plan view on line 4—4 of Fig. 3. Fig. 5 is a plan view of what is shown in Fig. 3.

The outside contour of distributor block 2 is of an accepted pattern and is provided 30 with a plurality of distributor posts as 5, 6, 7 equally spaced on a circle concentric with the axis of the device. Said posts extend through said block 2 to the inner face thereof and carry fixed therein respectively the 35 stems of a plurality of electrical contacts 8, 9, 10, and 11. The inner face of said block 2 is of frusto-conical shape and the inner faces of said contacts coincide with the conical portion 12 of said wall and terminate inwardly against the flat circular wall 13 of 40 said inner face. Contacts 8 to 11 are arranged in positions respectively, inclined to the axis of said block and disk 14 as shown particularly in Fig. 2 so that a protracted 45 field of contact is provided for the disk brush as it passes over each contact.

For rotation within the cavity formed by 50 portions 12 and 13 of the inner wall of block 2, frusto-conical distribution disk 14 is provided. Said disk has stem 15 projecting axially therefrom and said stem is provided

with an axial hole 16 therethrough for spring urged collector brush 17.

Said disk 14 has mounted therein for radial movement carbon brush 18 having an 60 angled nose for engagement with contacts 8 to 10. Said brush is contained within metal box-like member 19 fixed in disk 14 and is urged to engagement with contacts 8 to 10 and with the inner conical wall of block 2 by spring 20. Said box 19 has an inside width about twice the width or thickness of brush 18 and the remaining space in said box is occupied by a wiper 21 of felt or other suitable material. Said wiper is 65 provided with spring 22 to urge it outwardly for engagement with contacts 8 to 10 and with the conical wall 12 of block 2. Also said wiper is preferably placed in advance of brush 18, in the direction of rotation of 70 said brush.

For rotating disk 14 gear 23 is provided and said gear and disk may be connected by pin 24.

I claim:

1. A distributor head including in combination a frusto-conical distributor disk, a brush carried in said disk and having one end thereof protruding from the conical face of said disk, a block inclosing said disk and having a frusto-conical inner wall complementary to the frusto-conical outer wall of said disk, a plurality of electrical contacts arranged around the inner frusto-conical wall of said block and having their outer 90 faces respectively coincident with the conical face of said inner wall, a contact wiper carried by said disk and located ahead, in its direction of travel, of said brush and contiguous thereto, means for urging said brush into engagement with said contacts, independent means for urging said wiper into engagement with said contacts, means for rotating said disk, and electrical connections from said contacts to without said casing. 95

2. A distributor head including in combination a frusto-conical distributor disk, a carbon brush carried in said disk and having one end thereof protruding from the conical face of said disk, a block inclosing said disk 100 and having a frusto-conical inner wall complementary to the frusto-conical outer wall of said disk, a plurality of electrical contacts arranged around the inner frusto-conical wall of said block and having their outer 110 faces respectively coincident with the conical face of said inner wall, said contacts be-

ing inclined to the axis of said disk and block so that a protracted field of contact for said disk brush with said contacts is provided, a contact wiper carried by said disk and located ahead, in its direction of travel, of said brush and contiguous thereto, means for urging said brush into engagement with said contacts, independent means for urging said wiper into engagement with said contacts, means for rotating said disk, and electrical connections from said contacts to without said casing.

3. A distributor head including in combination a distributor disk, a carbon brush carried in said disk and having one end thereof protruding from the periphery of said disk, a block inclosing said disk and having an inner wall adjacent to and com-

plementary to the periphery of said disk, a plurality of electrical contacts arranged around said inner wall and having their outer faces respectively coincident with said wall, said contacts being inclined to the axis of said disk and block so that a protracted field of contact for said disk brush with said contacts is provided, a contact wiper carried by said disk and located ahead, in its direction of travel, of said brush and contiguous thereto, means for urging said brush into engagement with said contacts and independent means for urging said wiper into engagement with said contacts.

In witness whereof, I hereunto affix my signature this 8th day of April, 1918.

GEORGE T. DOCHTERMANN.
